[57] CLAIM

The ornamental design for experimental electronics trainer, as shown and described.

DESCRIPTION

FIG. 1 is a front elevational view of an experimental electronics trainer showing my new design.

FIG. 2 is a top plan view.

FIG. 3 is a rear elevational view on an enlarged scale.

FIG. 4 is a bottom plan view.

FIG. 5 is a left elevational view on an enlarged scale, and

FIG. 6 is a right side elevational view thereof.

FIG. 1

FIG. 2

FIG. 3
